UNITED STATES PATENT OFFICE

LEE DE FOREST, OF NEW YORK, N. Y., ASSIGNOR TO GEORGE K. WOODWORTH, OF BOSTON, MASSACHUSETTS.

WIRELESS-TELEGRAPH RECEIVING SYSTEM.

No. 852,381.

Specification of Letters Patent.

Patented April 30, 1907.

Application filed December 4, 1905. Serial No. 290,054.

To all whom it may concern:

Be it known that I, LEE DE FOREST, a citizen of the United States, and a resident of New York, in the county of New York and State of New York, have invented a new and useful Improvement in Wireless-Telegraph Receiving Systems, of which the following is a specification.

My invention relates to wireless telegraph receiving systems and has for its objects certain new and improved apparatus and circuit arrangements whereby the receiving circuit containing a receiver or responder and the receiving antenna may each be adjusted to the frequency or rate of vibration of the electromagnetic waves intended to affect said receiver; and whereby the effect of extraneous electrical forces, such as atmospheric electricity or static charges, which are not intended to affect said receiver, may be balanced and thereby neutralized, and hence prevented from affecting said receiver.

For the purpose of more fully disclosing my invention I have illustrated in the drawings accompanying and forming a part of this specification several forms of apparatus and circuit arrangements which in practice I have found well adapted for the purpose of carrying the hereinbefore stated objects into effect; but it will be understood that I do not limit myself to said forms of apparatus and circuit arrangements inasmuch as many modifications may be made therein without departing from the spirit of my invention.

In the drawings, Figure 1 represents in diagram a wireless telegraph receiving system embodying my invention; Fig. 2 represents a modification of the system shown in Fig. 1 and Figs. 3, 4 and 5 represent details of construction;

Referring more particularly to Fig. 1, A represents a loop antenna of the general type described in my prior patents and P, P¹ are two coils serially connected in said antenna and constituting the primary windings of a transformer, the secondary winding of which consists of the coil S which forms part of the tuned receiving circuit containing the condenser C and receiver R. As has long been known in the practice of wireless telegraphy, it is desirable to adjust the antenna and the circuit containing the receiver to the frequency of the electromagnetic waves which are intended to affect the receiver, and this,

in the present case, I accomplish by variable inductances constructed in the following manner: Upon a plate H or H¹ of glass or other insulating material is formed a flat spiral (shown at P¹ in Fig. 4, and at S, in Fig. 5) consisting of insulated wire so tightly wound that the adjacent convolutions are contiguous throughout their extent and the spiral forms a practically plane surface; and at a convenient point, such as 11 or 12, a contact arm 1 or 2 is pivoted to the plate, or, if desired, at two points, such as 13 and 14, two contact arms 4 and 5 are pivoted to said plate. Each contact arm is made of conducting material and carries at a point near its outer end a contact member p, q, r, or s of any suitable construction which makes contact with the convolutions of its spiral along the arc shaped path or paths a—a when the contact arm is rotated on its pivot, the insulation having been removed from the upper portion of the conductors forming the spirals along said paths a—a. The innermost convolution of each spiral is brought out to a binding post on the plate, as shown in Figs. 3, 4 and 5 at x, y and z to form one terminal of the spiral and the pivot of each contact arm forms the other terminal. Each plate H or H¹ is mounted upon a heavy base 15, 16, 17 of slate or other suitable material so that the spirals P, P¹ may be moved toward and away from each other and the spiral S, which preferably is placed between the spirals P, P¹, may be moved with respect thereto and so that, when once adjusted in position, each spiral will remain in such position. It will be obvious that the contact arms of the outer spirals may be grasped by the operator and rotated upon their pivots but that in order to rotate the contact arm of the inner spiral S, the contact arm 2 must be prolonged to form a handle 3.

It will now be apparent that when the spirals P, P¹ and S are placed as shown in Fig. 3 and are connected as shown in diagram in Fig. 1, said spirals constitute a transformer, the primaries P P¹ of which are serially connected with the loop antenna A, and the secondary S of which is inductively related to said primaries and forms a part of the receiving circuit. When the apparatus has been arranged and connected in this manner, the antenna and the receiving circuit may both readily be adjusted to any desired fre-

quency by varying the positions of the contact arms 1, 2 and 5, thereby varying the inductance of the spirals as well as the number of effective convolutions thereof in a continuous, as distinguished from an intermittent, manner, and hence permitting an exceedingly fine adjustment,

I prefer, as shown in Figs. 1 and 4, to employ two contact arms with one of the primaries, herein shown as the spiral P^1 , so as to be able at will to cause the oscillations developed in the antenna to have either a differential or a conjunctional effect upon the secondary S and the receiving circuit of which said secondary forms a part. For example as shown in Fig. 1, the magnetic fields developed in the spirals P and P^1 will have a conjunctional effect upon the spiral S if the current flows through P and P^1 in the same direction, and hence if it be desired that the magnetic fields developed in said spirals P and P^1 have a differential effect upon the spiral S under said conditions of current flow, the antenna is disconnected from the pivot 14 of the contact arm 5 and is connected to the spiral at the point x while the point n is connected to the pivot 13 of the contact arm 4 as shown in Fig. 2.

In the absence of interference by extraneous electrical forces it is desirable to have the oscillations passing through the coils P , P^1 exert a conjunctional effect on the coil S and in the presence of such interference it is desirable that such effect be a differential one as hereinafter explained. In any event, the connection of the antenna to the arm 5 or the arm 4 must be determined experimentally, for, as will be obvious, the direction of current flow through P and P^1 at any given instant of time depends altogether upon the relation of the length of the electrical waves impinging upon the antenna to the length of the antenna itself.

In view of the foregoing, it will be seen that the spirals P , P^1 and S each constitute an exceedingly simple and effective wireless telegraph tuning device whereby the first object of my invention may be realized.

The second object of my invention may be effected by means of the above described transformers in the following manner: When the receiving operator perceives by the signal indications in the head telephone T , included in circuit with the receiver R and potentiometer Q which regulates the current from the battery B , that the reception of a message is being interfered with by outside electrical forces, natural or artificial, he first connects the primaries P , P^1 so that they will act differentially with respect to the secondary S . He then adjusts the effective number of convolutions in each primary until the condition known as "silence in the telephone" is attained. To arrive at such condition, it is sometimes necessary to move the primaries

toward or away from each other and, possibly, as a final adjustment, to move the secondary with respect to the primaries in order to balance the effect of any inequality of the two sides of the loop antenna. When such an adjustment has been obtained that the effects of the two primaries on the secondary are equal and opposite, no electrical impulse whatever, whether it be the impulse desired to be received, or a disturbing impulse, or a static charge induced by natural causes in the antenna, will have the slightest effect on the receiver because the effects of such impulses on the receiving circuit are now balanced and thereby neutralized. In order, therefore, to receive the signals intended for the receiving system, all that is necessary is to slightly disturb the aforesaid balance by slightly moving the arms of the primaries P or P^1 , or by slightly moving the secondary S with respect to said primaries. I am not prepared at the present time to give any reason or reasons why such slight movement of one of the primaries or of the arms of said primaries will unbalance the system for electrical oscillations of the frequency to which the receiving circuit is attuned and hence permit such oscillations to influence the receiver, and still not unbalance the system for impulses or other frequencies or for static charges and hence prevent such impulses and charges from influencing the receiver; but so far as the static charges are concerned, the explanation probably is found in the fact that the effects of such charges are unidirectional and that therefore the balance of such effects on the secondary is not disturbed by the slight change produced in the inductance by the aforesaid movement of one of the primaries, or of the arms thereof. Whatever the explanation may be, I have succeeded with the system herein described in receiving signals in the presence of the unusually large static influences which exist in tropical and semi-tropical climates.

The elimination of static effects may be accomplished also by the system shown in Fig. 2, in which one side of the loop antenna A is connected to a circuit consisting of two branches m 11 n and m n which, by a conductor containing the condenser C^1 , is connected to earth at E . The two primaries P and P^1 are serially connected in said branches, and hence are serially connected with the antenna, but otherwise the arrangement of spirals is the same as in Fig. 1. The antenna is shown as a multiple loop antenna in Fig. 2 but it is to be understood that a single loop antenna may be substituted therefor. The wires of the multiple loop antenna are secured to the mast (not shown) by the spar K and are separated by the spreaders F F which are held in the positions indicated by the guys G G provided with the strain insulators I I . The side of the antenna which is not connected to

the transformer is connected to earth at E through the adjustable inductance L, which is varied by the sliding contact t. As indicated on dotted lines, this contact may take the position r, thereby entirely cutting out the inductance L, and affording a path of low impedance to earth for the outside electrical forces or static influences.

From the description above set forth of the operation of the system shown in Fig. 1, the operation of the system shown in Fig. 2 will be apparent, and it will also be apparent that in the system of Fig. 2, the inequality necessarily existing between the two sides of any loop antenna does not enter as a disturbing factor into the operation of balancing the effects developed in the primaries upon the secondary. In view of the fact, as above stated, that the spirals P, P¹, and S consist of insulated wire so tightly wound that the adjacent convolutions are contiguous throughout their extent, it will be apparent that the variation of the inductance and the number of the effective convolutions of said spirals, which is effected by the rotation of the arms 1, 2, 4 and 5 about their respective pivots, will be continuous as distinguished from intermittent for the reason that the contacts, with which said arms are provided, do not completely leave one convolution before arriving on the adjacent convolution.

I am aware that flat spirals have heretofore been proposed for use as transformer windings in wireless telegraphy but I know of no case in which the inductance and the number of effective turns of such spirals can be varied in a continuous manner, thereby permitting the exceedingly fine adjustments required for effective tuning and for the elimination of foreign impulses.

Having fully described my invention, I claim:

1. In a wireless telegraph receiving system, the combination with a loop antenna and a tuned receiving circuit, of a transformer having two primary windings serially connected in said loop antenna and a secondary winding inductively related to said primary windings and forming part of said tuned receiving circuit.

2. In a wireless telegraph receiving system, the combination with a loop antenna and a tuned receiving circuit, of a transformer having as its primary windings two flat spirals serially connected in said loop antenna, and a secondary winding, also consisting of a flat spiral, inductively related to said primary windings and forming part of said tuned receiving circuit.

3. In a wireless telegraph receiving system, the combination with a loop antenna and a tuned receiving circuit, of a transformer having two adjustable primary windings serially connected in said loop antenna, and an adjustable secondary winding inductively related to said primary windings and forming part of said tuned receiving circuit.

tively related to said primary windings and forming part of said tuned receiving circuit.

4. In a wireless telegraph receiving system, the combination with a loop antenna and a tuned receiving circuit, of a transformer having two primary windings serially connected in said loop antenna, means whereby said transformer windings may be moved toward and away from each other, and a secondary winding inductively related to said primary windings and forming part of said tuned receiving circuit.

5. In a wireless telegraph receiving system, the combination with a loop antenna and a tuned receiving circuit, of a transformer having two primary windings serially connected in said loop antenna, a secondary winding inductively related to said primary windings and forming part of said tuned receiving circuit, and means whereby said secondary winding may be moved with respect to said primary windings.

6. In a wireless telegraph receiving system, the combination with a loop antenna and a tuned receiving circuit, of a transformer having two primary windings serially connected in said loop antenna, a secondary winding placed between said primary windings and forming part of said tuned receiving circuit and means whereby said secondary winding may be moved with respect to said primary windings.

7. In a wireless telegraph receiving system, an antenna, a circuit consisting of two branches connecting said antenna to earth, a transformer having two primary windings each serially connected in a different one of said branches, and a secondary winding inductively related to said primary windings and forming part of a tuned receiving circuit.

8. In a wireless telegraph receiving system, an antenna, a circuit consisting of two branches connecting said antenna to earth, a transformer having two primary windings each serially connected in a different one of said branches, a secondary winding inductively related to said primary windings and forming part of a tuned receiving circuit, and a circuit connecting the upper end of said antenna to earth.

9. In a wireless telegraph receiving system, an antenna, a transformer having two primary windings associated therewith, a secondary winding inductively related to said primary windings and means for causing the electrical oscillations developed in said antenna to have either a differential or a conjunctive effect on said secondary winding.

10. The combination with a wireless telegraph receiving antenna of an oscillation transformer consisting of three flat spirals, two of which are primaries and one of which is a secondary and heavy bases each having a different one of said spirals mounted thereon

- whereby said primaries may be moved with respect to said secondary and said secondary may be moved with respect to said primaries.
11. The combination with a wireless telegraph receiving antenna of an oscillation transformer consisting of three flat spirals, two of which are primaries and one of which is a secondary, said primaries being constructed and arranged to act differentially upon said secondary and means whereby the number of effective convolutions of said primaries and said secondary may be varied in a continuous manner.
12. The combination with a wireless telegraph receiving antenna of an oscillation transformer consisting of three flat spirals, two of which are primaries and one of which is a secondary, said primaries being constructed and arranged to act differentially upon said secondary means whereby said primaries may be moved toward and away from each other and means whereby said secondary may be moved with respect to said primaries.
13. In a wireless telegraph receiving system, the combination with a loop antenna and a receiving circuit, of a transformer having as its primary windings two flat spirals serially connected in said loop antenna, a secondary winding, also consisting of a flat spiral, inductively related to said primary windings and forming part of said receiving circuit, and means for varying the number of effective convolutions of said flat spirals.
14. The combination with a wireless telegraph receiving antenna of an oscillation transformer consisting of three flat spirals, two of which are primaries and one of which is a secondary, said primaries being constructed and arranged to act differentially upon said secondary and means whereby said secondary may be moved with respect to said primaries.
15. In a wireless telegraph receiving system, an antenna, a circuit consisting of two branches connecting said antenna to earth, a transformer having as its primary windings two flat spirals each serially connected in a different one of said branches, and a secondary winding, consisting of a flat spiral, inductively related to said primary windings and forming part of a tuned receiving circuit.
16. In a wireless telegraph receiving system, an antenna, a circuit consisting of two branches connecting said antenna to earth, a transformer having two adjustable primary windings each serially connected in a different one of said branches, and an adjustable secondary winding inductively related to said primary windings and forming part of a tuned receiving circuit.
17. In a wireless telegraph receiving system, an antenna, a circuit consisting of two branches connecting said antenna to earth, a transformer having two primary windings each serially connected in a different one of said branches, means whereby said transformer windings may be moved each with respect to the other, and a secondary winding inductively related to said primary windings and forming part of a tuned receiving circuit.
18. In a wireless telegraph receiving system, an antenna, a circuit consisting of two branches connecting said antenna to earth, a transformer having two primary windings each serially connected in a different one of said branches, a secondary winding inductively related to said primary windings and forming part of a tuned receiving circuit, and means whereby said secondary winding may be moved with respect to said primary windings.
19. In a wireless telegraph receiving system, an antenna, a circuit consisting of two branches connecting said antenna to earth, a transformer having two primary windings each serially connected in a different one of said branches, a secondary winding placed between said primary windings and forming part of a tuned receiving circuit, and means whereby said secondary winding may be moved with respect to said primary windings.
20. In a wireless telegraph receiving system, an antenna, a circuit consisting of two branches connecting said antenna to earth, a transformer having as its primary windings two flat spirals, each serially connected in a different one of said branches, means whereby the number of effective convolutions of said primary windings may be varied, a secondary winding, consisting of a flat spiral, inductively related to said primary windings and forming part of a receiving circuit, and means whereby the number of effective convolutions of said secondary winding may be varied.

In testimony whereof, I have hereunto subscribed my name this 29th day of Nov. 1905.

LEE DE FOREST.
